SPRING STRUCTURE

Vito Asaro, Detroit, Mich., assignor to L. A. Young Spring & Wire Corporation, Detroit, Mich.

Application June 19, 1941, Serial No. 398,747

12 Claims. (Cl. 155—181)

This invention relates to improvements in spring structures.

The main objects of this invention are:

First, to provide an improved spring structure having a top border frame which is effective in supporting the upholstery, effectively resists stresses applied in a horizontal direction, and at the same time may be formed of light stock.

Second, to provide a border frame for spring structures which may be readily constructed in any desired outline for the purpose of supporting the upholstery or providing a cushion structure of desired shape, and at the same time one which may be readily applied to a spring structure.

Objects pertaining to details and economies of the invention will definitely appear from the description to follow. The invention is defined in the claims.

A structure which embodies the features of the invention is clearly illustrated in the accompanying drawings, in which:

Fig. 1 is a fragmentary plan view of a spring structure embodying the features of my invention, the bottom frame being omitted and only a portion of the top frame illustrated.

Fig. 1A is a plan view of a top frame embodying my invention formed as a complete unit.

Fig. 2 is an enlarged fragmentary view of the border frame showing the relation of the members thereof and a preferred embodiment of strut member.

Fig. 3 is an enlarged sectional view on line 3—3 of Fig. 2.

Fig. 4 is an enlarged sectional view on line 4—4 of Fig. 2.

Fig. 5 is a section corresponding to that of Fig. 4, slightly modified.

Fig. 6 is a fragmentary plan view of the border frame of the invention embodying a modified form of strut member.

Fig. 7 is a fragmentary section on line 7—7 of Fig. 6.

Fig. 8 is a fragmentary plan view of another form or embodiment of the invention.

Fig. 9 is a fragmentary section on line 9—9 of Fig. 8.

Fig. 10 is a fragmentary plan view of still another form or embodiment of my invention.

Fig. 11 is a section on line 11—11 of Fig. 10.

In the accompanying drawings the body springs 1 are of the helical type mounted on a suitable base including cross members 2. The base frame is not illustrated and only portions of the springs are illustrated. The adjacent springs of the

spring assembly are connected by the crossed helical tie members 3.

My improved border frame comprises a continuous outer frame member 4 which is formed of flat wire stock disposed flatwise or with the flat sides horizontally. This outer frame member is conformed to support the upholstery in the desired outline. An inner border frame member 5 is provided which is also formed of flat wire stock disposed flatwise or with the flat sides horizontally. The outer frame member comprises a front portion 6, rear portion 7 and end portions 8. The inner frame member comprises a front portion 9 and end portions 10. The rear ends of the end portions 10 are deflected or bent outwardly at 11 and secured to the side portions 8 adjacent the rear ends thereof by means of the clips 12.

Corresponding portions of these inner and outer members are arranged in spaced substantially parallel relation. They are rigidly and fixedly connected by the spaced strut or tie members 13 which are of sheet metal stampings and of substantial width so that they form effective strut or brace members which also have a tie action as well as a bracing action against wracking movement of the frame members. The ends 14 of these strut members are folded around the frame members into clamping engagement therewith.

The strut members in the embodiment illustrated in Figs. 1 to 4 have oppositely disposed offsets 15 in the side edges thereof which provide shoulders 16 in supporting engagement with the adjacent edges of the frame member, see Figs. 2, 3 and 4. Overlapping portions of the strut members are preferably secured to the frame members as indicated at 17. This may be accomplished by providing the clamping ties with suitable prick-punch projections embedded in the frame members. The offsetting shown in this embodiment provides substantially spaced frame member engaging shoulders which is of advantage in that an effective bracing action results, also a more effective engagement of the parts than results where the offsets extend entirely or substantially across the struts.

In Fig. 5 the extreme edges 21 of the parts 14 which are clamped around the frame members are folded or turned inwardly into abutting engagement with shoulders 16.

In the embodiment shown in Figs. 6 and 7 the strut members 18 have offsets 19 of substantially greater depth and of general rectangular outline

as compared to the offsets of the embodiment shown in the preceding figures.

In the embodiment of Figs. 8 and 9 the intermediate portion 23 of the strut members 22 is longitudinally curved and tongue-like portions 24 are struck out therefrom to provide frame member engaging lugs. These parts 24 may be struck out before the strut members are applied or during the operation of applying the strut members.

In the embodiment shown in Figs. 10 and 11 the strut members 25 have a central intermediate portion 26 thereof offset to provide the shoulders 27 which are in supporting engagement with the adjacent edges of the frame members.

The border frame shown in Fig. 1-A is assembled as a complete frame or unit to be applied to the spring assembly in completing or assembling the structure. It will be understood that the shape of the frame may be and is in commercial practice varied or changed according to the shape of finished cushion desired. This frame is secured to the outer body springs by means of clips 28, some of which in the embodiment illustrated in Fig. 1 connect certain of the springs to the outer member of the frame and others to the inner member of the frame. The frame structure is very rigid and resistant to stresses which tend to distort the same in use; at the same time it is formed of comparatively light stock and is of comparatively light weight, both of which are features greatly to be desired.

The structure is in effect a truss structure and is effective in resisting bending and wracking strains, the strut members being of substantial width and each strut member engaging each frame member at spaced points is very effective to that end.

I have not attempted to illustrate further adaptations and applications of the structure of the invention as it is believed the disclosure made will enable those skilled in the art to embody or adapt the invention as may be desired.

Having thus described my invention what I claim as new and desire to secure by Letters Patent is:

1. In a spring structure, the combination with upright body springs, of a border frame comprising a continuous horizontally disposed outer border member formed of flat wire stock and comprising front, rear and end portions, a horizontally disposed inner frame member also formed of flat wire stock and having front and end portions disposed in spaced substantially parallel relation to the front and end portions of the outer frame member, said frame members being disposed with their flat sides horizontal, the ends of the side portions of the inner member being deflected outwardly and secured to the end portions of the outer frame member adjacent the rear ends thereof, and strut members connecting said outer and inner frame members, said strut members being sheet metal stampings of substantial width and having oppositely disposed offsets at the side edges thereof, the ends of which constitute spaced pairs of shoulders which are in supporting engagement with the adjacent edges of the frame members, the ends of said strut members being folded around said frame members in clamping relation therewith, the outer springs being secured to said border frame.

2. In a spring structure, the combination with upright body springs, of a border frame comprising a continuous border member comprising

front, rear and end portions, an inner frame member having front and end portions disposed in spaced substantially parallel relation to the front and end portions of the outer frame member, the ends of the side portions of the inner member being secured to the end portions of the outer frame member adjacent the rear ends thereof, and strut members connecting said outer and inner frame members, said strut members being sheet metal stampings having offsets therein constituting shoulders which are in supporting engagement with the adjacent edges of the frame members, the ends of said strut members being clamped around said frame members, the outer body springs being secured to said border frame.

3. A frame for spring structures comprising a continuous outer border member comprising front, rear and end portions, an inner frame member having front and end portions disposed in spaced relation to the front and end portions of the outer frame member, the ends of the side portions of the inner member being secured to the end portions of the outer member adjacent the rear ends thereof, and strut members connecting said outer and inner frame members, said strut members being sheet metal stampings of substantial width having the ends thereof clamped upon said frame members, intermediate portions of said strut members being offset to provide shoulders engaging the adjacent edges of said frame members and coacting with the portions of the strut members clamped around said frame member fixedly engaging the frame members.

4. A frame for spring structures comprising a continuous horizontally disposed outer border member formed of flat wire stock and comprising front, rear and end portions, a horizontally disposed inner frame member also formed of flat wire stock and having front and end portions disposed in spaced relation to the front and end portions of the outer frame member, said frame members being disposed with their flat sides horizontal, the ends of the side portions of the inner member being secured to the end portions of the outer member, and strut members connecting said outer and inner frame members, said strut members being sheet metal stampings having flat surfaces parallel to and engaging the flat sides of said frame members and having the ends thereof clamped upon said frame members and rigidly engaging the latter to prevent relative rotation of the strut and frame members at the clamped connection, intermediate portions of said strut members being conformed to bracingly engage the adjacent edges of said frame members.

5. A border frame for spring structures comprising inner and outer border members of flat wire stock disposed in spaced relation with their flat sides horizontal, and strut members connecting said outer and inner frame members, said strut members being sheet metal stampings of substantial width and having oppositely disposed offsets at the side edges thereof, the ends of which constitute spaced pairs of shoulders which are in bracing engagement with the adjacent edges of the frame members, the ends of said strut members being folded around said frame members in clamping relation therewith rigidly engaging the latter to prevent relative rotation of the strut and frame members at the clamped connection, parts of said strut members

overlapping said frame member being embed-
dingly secured thereto.

6. A border frame for spring structures comprising inner and outer border members of flat wire stock disposed in spaced relation with their flat sides horizontal, and strut members connecting said outer and inner frame members, said strut members being sheet metal stampings of substantial width and having oppositely disposed offsets at the side edges thereof, the ends of which constitute pairs of shoulders which are in bracing engagement with the adjacent edges of the frame members, the ends of said strut members being folded around said frame members in clamping relation therewith.

7. A border frame for spring structures comprising inner and outer border members of flat wire stock disposed in spaced relation with their flat sides horizontal, and strut members connecting said outer and inner frame members, said strut members being sheet metal stampings of substantial width and having oppositely disposed offsets at the side edges thereof, the ends of which constitute spaced pairs of shoulders which are in bracing engagement with the adjacent edges of the frame members, the ends of said strut members being folded around said frame members in clamping relation therewith with the edges thereof turned inwardly into abutting relation to said shoulders.

8. A border frame for spring structures comprising horizontally disposed inner and outer members of flat section disposed in spaced relation with their flat sides horizontal, and strut members of sheet metal connecting said frame members at spaced intervals and having offsets intermediate said frame members providing pairs of spaced shoulders which are in engagement with the adjacent edges of the frame members, the ends of said strut members being clamped upon said frame members and rigidly engaging the latter to prevent relative rotation of the strut and frame members at the clamped connection.

9. A border frame for spring structures comprising inner and outer members of angular section disposed in spaced relation, and strut members of sheet metal connecting said frame members at spaced intervals and having offsets providing shoulders which are in bracing engage-

ment with the adjacent edges of the frame members, the ends of said strut members being clamped around said frame members in rotation-resistant relation to opposed sides thereof.

10. A border frame for spring structures comprising inner and outer border members of flat section disposed in spaced substantially parallel relation with their flat sides horizontal, and strut members of sheet metal connecting said frame members at spaced intervals, said strut members having portions thereof struck up to provide frame member engaging portions, the ends of said strut members having flat surfaces parallel to and engaging the flat sides of said frame members and being clamped upon said frame members and rigidly engaging the latter to prevent relative rotation of the strut and frame members at the clamped connection.

11. A border frame for spring structures comprising horizontally disposed inner and outer border members of flat section disposed in spaced relation with their flat sides horizontal, and strut members connecting said frame members at spaced intervals and formed of sheet metal pieces of substantial width having the ends thereof provided with flat surfaces parallel to and engaging the flat sides of the side members and clamped upon said side members, and oppositely disposed intermediate portions offset to provide spaced shoulders which are in bracing engagement with the inner edges of the frame members.

12. A border frame for spring structures comprising horizontally disposed inner and outer border members of flat section disposed in spaced relation with their flat sides horizontal, and strut members connecting said frame members at spaced intervals and formed of sheet metal pieces of substantial width having the ends thereof provided with flat surfaces parallel to and engaging the flat sides of the side members and clamped upon said side members rigidly engaging the latter to prevent relative rotation of the strut and frame members at the clamped connection, and intermediate portions thereof conformed to provide portions in supporting engagement with the inner edges of the frame members.
